UNITED STATES PATENT OFFICE.

GEORGE E. ADAMS, OF PROVIDENCE, RHODE ISLAND, ASSIGNOR TO THE TRAUT & HINE MANUFACTURING COMPANY, OF NEW BRITAIN, CONNECTICUT.

DESIGN FOR A BUCKLE.

SPECIFICATION forming part of Design No. 22,132, dated January 17, 1893.

Application filed October 27, 1892. Serial No. 450,184. Term of patent 3½ years.

To all whom it may concern:

Be it known that I, GEORGE E. ADAMS, of Providence, in the county of Providence and State of Rhode Island, have invented and produced a new and original Design for Buckles, of which the following is a specification, reference being had to the accompanying drawing, and to the letters of reference marked thereon.

Said drawing represents in front elevation 10 a buckle embodying my present design and applied to a suspender web.

The essential feature of the design will at once be seen to consist in the ornamental bow knot configuration given to the portion over-

15 lying the web. In the configuration shown, the bows A extend horizontally and are attached along the upper edge to a bar B, giv-

ing the appearance of being suspended from said bar, and the two ends C project downward diverging from each other and are pointed to resemble ends of ribbon. At the center a vertical band D represents the knot proper, and suitable creases are formed and ornamentations are applied as shown, to increase the resemblance to a knot of ribbon 25 or fabric.

What I claim and desire to secure by Letters Patent is:

The design for a buckle herein shown and described.

GEORGE E. ADAMS.

Witnesses:

E. N. STANLEY,
G. W. TRAUT.
